SHOE BOTTOM ATTACHING APPARATUS

George H. Barge, Jamaica, N. Y., assignor to
 Barge Electric Shoe Cement Press, Inc., a corporation of New York

Application December 9, 1932, Serial No. 646,357

23 Claims. (CL. 12—33)

This invention relates to apparatus for attaching bottoms to shoes, and more particularly to apparatus of this type for use in cementing or otherwise adhesively attaching, leather, or other soles to shoes, boots or the like, wherein the lasted portions of shoes or the like and the soles to be secured thereto have been previously coated with an adhesive and are then subjected to pressure within the apparatus until the cement or other adhesive has set.

Various types of apparatus have heretofore been used for these general purposes, and the primary object of the present invention is to simplify and improve the construction and operation of such apparatus.

Another object of the invention is to provide apparatus of this type adapted to support the shoe or the like upon a flexible cushion during the cementing operation, the cushion being constructed to apply pressure uniformly and evenly upon the shoe bottom and around the edges of the sole or the like to be attached to the shoe.

Still another object of the invention is to provide a handy and convenient portable half-sole cementing apparatus for use by shoe repairers as well as shoe manufacturers, for applying half-soles to shoes.

A further object of the invention is to provide means adapted to overlie and engage the welt of the shoe to resist the pressure of the pressure-applying means against the underside of the edge of the sole, said pressure resisting means being adjustable for adaptation to cooperate with shoes of different sizes and shapes.

A still further object of the invention is to provide an apparatus having the advantages above referred to and which in addition is adapted to apply a full sole to a lasted shoe or the like, this machine being particularly adapted for use in the multiple production of shoes in the factory.

It is a still further object of the invention to provide a shoe sole attaching apparatus having a flexible cushion or pressure-applying member wherein the pressure is exerted by a fluid such as air, water or steam.

In the accompanying drawings the invention is shown merely by way of example and in preferred form, and obviously many modifications and variations may be made therein without departing from the spirit of the invention. It is to be understood, therefore, that the invention is not limited to any specific form or embodiment except insofar as such limitations are specified in the appended claims.

In the drawings:

Fig. 1 is a side elevation of a shoe bottom cementing machine constructed according to the present invention and particularly adapted for applying half-soles to shoes in the repairing of the same;

Fig. 2 is a top plan view of the device shown in Fig. 1, certain of the parts being broken away more clearly to show the parts below;

Fig. 3 is a front elevation of the device shown in Fig. 1;

Fig. 4 is a transverse section of the same;

Fig. 5 is a vertical longitudinal section of a modification of the device adapted for use in cementing a full sole to a shoe bottom;

Fig. 6 is a top plan view of the device shown in Fig. 5;

Fig. 7 is a front elevation of a work table adapted to support a multiplicity of shoe bottom cementing devices as shown in Fig. 5, for use in a shoe manufactory;

Fig. 8 is a view similar to Fig. 5, showing the apparatus equipped with the improved sole edge pressure resisting device;

Fig. 9 is a top plan view of the sole edge pressure resisting device; and

Fig. 10 is a transverse section taken on the line 10—10 of Fig. 8.

In the drawings, the shoe bottom cementing machine includes a generally oval shaped hollow base 10, having foot portions 11 whereby the same may rest upon any suitable surface such as a work bench or table or the like. This hollow base 11 in this instance includes an outwardly extending rim portion 12 upon which a flexible pressure-applying or distributing member 13 is such as a piece of heavy leather or the like is adapted to be superimposed, this pressure-applying member 13 being of such shape that when the same is acted upon by pressure exerting means as will be hereinafter described, the same will assume a proper position for performing the pressure-applying operation. The outer edge 14 of the pressure-applying member 13 is in this instance secured at the outstanding rim portion 12 of the hollow base 10 by means of a rim plate 15 of general horseshoe shape as seen in Fig. 2, or of general oval shape as seen in Fig. 6. The rim plate 15 in each instance is adapted to be secured to the hollow base portion 10 by means of bolts or the like 17 which extend through aligned holes in the rim plate 15 and the rim portion 12, the outer edge of the pressure-applying member 13 being thus securely clamped between the rim plate and the rim of the base member 10.

55

One defect of prior constructions adapted for purposes similar to those of the present invention is that the pressure-applying member is acted upon over its entire area by pressure exerting means, which mode of exerting pressure results in an uneven application of pressure over the shoe bottom, because in such cases the pressure-applying member acts merely as an air cushion or pillow. In accordance with the present invention, the pressure-applying member 13 is adapted to constitute a true pressure-applying medium in contradistinction to air cushions or pillows as heretofore used, and for the present purposes I provide within the hollow base portion 10 an annular inflatable pressure exerting member 18 extending around the inner walls of the hollow base portion 10, this inflatable member 18 being equipped with a suitable air or other fluid inlet valve 19 the stem 20 of which extends through a hole 21 provided preferably at the front of the hollow base 10.

A shoe or the like 22, upon which a half-sole is to be attached as seen in Figs. 1 to 4 inclusive, is first equipped with a last 23 and is then placed upon the pressure-applying member 13, the device in the figures referred to being constructed so that the sole portion of the shoe occupies a position substantially at the center of the pressure-applying member. To hold the shoe tightly down against the pressure-applying member, means are provided to cooperate with the latter, these means in the present instance including a reach arm 24 pivotally mounted at 25 between lugs 26 and 27 rising from the rim plate 15. This reach arm 24 has secured thereto a depending abutment member 27, this abutment member 27 having a generally rounded base 28, and being pivotally mounted upon the reach arm 24 in any suitable manner as for instance by means of a bolt 29 adapted to be passed through one of the holes 30 at the forward part of the reach arm 24. These holes 30 afford different positions of adjustment for the abutment member 27 to accommodate shoes of different sizes. The underside of the base portion 28 of the abutment 27 is preferably provided with a layer of felt or other cushioning means 31 to prevent injury to the surface of the shoe with which the bottom of the member is engaged.

To hold the shoe in proper position during the pressure-applying operation, the rearward portion of the reach arm 24 is provided with a depending lug 32 pivotally mounted on the reach arm as seen at 33, in substantially the same manner in which the member 27 is mounted on said reach arm, the depending lug 32 being adapted to be pivotally secured at any one of a plurality of apertures 34 at the rear of the reach arm. This lug 32 is adapted to rest within a suitable recess provided above the heel portion of the last 23 as indicated at 35.

The reach arm with its abutment member 27 and depending lug 32 is adapted to press the shoe 22 firmly down against the pressure-applying member 13, which shoe 22, as will be understood, has previously had a half-sole or the like 36 adhesively applied thereto. To hold the reach arm firmly in the pressure-applying position, a yoke arm 37, pivotally mounted between lugs 38, rising from the rearward part of the rim plate 15, is adapted to have its upper portion engage in one of a plurality of notches 40 provided at the extreme rearward edge of the reach arm 24.

The shoe which is to have a sole cemented thereto having been positioned as already de-

scribed, the reach arm 24 is depressed to place the shoe in the pressure-applying position, and the reach arm 24 is secured in such position by engagement of the yoke arm 37 with an appropriate notch 40. Air (or whatever pressure exerting fluid is being used) is then admitted to the inflatable member 18 through the valve stem 20 in any suitable manner, thereby inflating the member 18 sufficiently to exert the desired pressure on the pressure-applying member 13 against the bottom of the shoe. It will be seen that the provision of the member 18 in this instance enables the pressure to be exerted at its greatest force around the outer edges of the shoe while at the same time causing the pressure-applying member 13 to exert an upward drawing pressure against the shoe bottom, thus enabling all parts of the sole to be evenly pressed and firmly held against the shoe, and particularly at the end of the sole which crosses the shank, and also the outer edges of the shoe sole 36 (see Figs. 1 and 4). Thus the shoe sole 36 is very firmly united with the bottom of the shoe.

The modification of the invention shown in Figs. 5 and 6 is substantially similar in its essential aspects to the device shown in Figs. 1 to 4 inclusive. The device as shown in Figs. 5 and 6, however, is particularly adapted to apply a full sole 41 to the bottom of shoe 42, the rearward lug 32 in this instance being adapted to perform the dual function of acting as an abutment member similar to the member 27 and at the same time maintaining the lasted shoe in position upon the pressure-applying member. The modification of the invention shown in Figs. 5 and 6 is particularly for use in the multiple production of shoes in factories; and for the latter purpose a plurality of the shoe bottom cementing devices, as seen at 43 (Fig. 7), are adapted to be mounted upon a rotary work table 44, the work table 44 being mounted on a suitable stand 45 and adapted to be rotated to present the devices 43 successively to a workman by means of a suitable foot lever 46. In this instance, suitable means are preferably provided to operate in conjunction with the foot lever 46 to exhaust air from and supply air to the pressure exerting members of the devices 43 as the same are presented before the workman for removal of a shoe on which the sole cementing operation has been completed and replacing the same with a shoe upon which the sole cementing operation is to be performed. The devices 43 mounted on the work table 44 as described, are preferably of such number as to correspond with the normal speed of the workman in placing the shoes upon and removing them from the devices 43 so that the cementing operation will be completed during the period of a complete revolution of the table 44.

The embodiment illustrated in Figs. 8 to 10, inclusive, is substantially like that shown in Figs. 5 and 6, but in addition is equipped with means for overlying the welt of the shoe to resist the pressure applied to the edges of the sole, thereby not only insuring the proper application of pressure to this portion of the sole, but also preventing the said edges from turning upwardly under the pressure.

This supplementary pressure resisting means comprises a holder 50 provided at opposite ends with upstanding yokes 51 adapted to be secured to the reach arm 24 by means of bolts 52 passing through aligned apertures in the yokes 51 and the reach arm 24. The holder 50 is formed on opposite sides with a series of slots 53, the purpose of

which will be hereinafter set forth. This holder 50 is adapted to support a plurality of members 55, which go to make up a substantially U-shaped segmental ring (see Fig. 9), the members 55 being suspended from the holder 50 each by a jointed link 56, so formed and arranged as to project laterally from the holder 50 to span the toe portion of a shoe and being adjustable vertically, horizontally, and laterally so as to cooperate with 10 shoes of different sizes and shapes.

The links 56 comprise each a main portion 57 formed on one end with a shoulder 58 from which there projects a stud 59. The stud 59 is adapted to be passed through one of the slots 53 in the 15 holder 50 until the shoulder 58 engages the underside of the holder 50, in which position the portion 57 is held by a wing nut 60 screwed on the stud 59. The other end of the portion 57 is formed with a hollow boss 61, which serves as a bearing 20 for a studded boss 62 clamped therein by a wing nut 63. The boss 62 is formed with a screw-threaded aperture 64 adapted to receive the threaded end of a stud 65 formed on the member 55.

25 As already stated, the construction and manner of attachment of the links 56 are such that the members 55 may be adjusted vertically, horizontally, and laterally so as to cooperate with shoes of different sizes and shapes. Since the 30 adjustments which may be made are the same in the case of each of the links, the manner in which the adjustments are effected will be described in connection with but one of the links. The vertical adjustment is effected by screwing 35 up or unscrewing the stud 65 in the boss 62, and the horizontal adjustment is effected by loosening the wing nut 60 and sliding the link 56 (which carries the member 55 with it) fore-and-aft any distance within the limit of the slot 53, the link 40 being maintained in any set position by tightening the nut 60. To effect a lateral adjustment of the member 55, the wing nut 63 is loosened and the boss 62 rotated in the bearing 61 and then clamped in set position by tightening the nut 63. 45 Furthermore, a slight rotation for aligning the member 55 with the welt of the shoe may be effected, when desired, by rotating the stud 65 or by loosening the wing nut 60 and rotating the entire connecting link 56, the former, however, 50 being the usual method employed.

Thus, it will be seen that the additional pressure resisting means provided by the present invention to cooperate with the welt of the shoe is capable of substantially universal adjustment, in 55 order that it may be adapted to cooperate with shoes of different sizes and shapes. Furthermore, the links are independently detachable from the holder and are formed in sections so that substitution and replacement of the parts may be 60 effected at a minimum cost.

In the use of the shoe bottom attaching apparatus equipped with the additional pressure resisting device, the lasted shoe is placed in position 65 on the pressure-applying member in the manner already described. However, before the lock-up is made by the engagement of the yoke member 37 with one of the notches 40, the wing nuts 63 are loosened (or may already have been loosened to permit the positioning of the shoe in the ordinary manner) and the members 55 swung outwardly away from the shoe and screwed up or unscrewed in the bosses 62 to shorten or 70 lengthen the link, as desired, to secure proper engagement of the members with the welt of the shoe. When the links 56 have all been ad-

justed to the desired length, if necessary, the wing nuts 60 may be loosened and the links shifted in a fore-and-aft direction properly to locate the members 55 along the welt. With these adjustments finally made, the lock-up between the 5 yoke 37 and the reach arm 24 is effected, the pressure exerting member 18 inflated, and so on, all subsequent operations proceeding as usual.

Of course, it is to be understood that the different steps in making the adjustments need 10 not necessarily follow the order outlined above, but may be made in any order desired. Further, although the welt gripping device has been shown only in connection with the full sole attaching apparatus, it may be applied to the half soles 15 unit equally as well.

Having thus described my invention, what I claim is:

1. A shoe bottom attaching apparatus including, in combination, pressure-applying means, 20 means for holding a shoe in position to resist the pressure of said pressure-applying means against the shoe sole, and additional means comprising a unit of disconnected sections adapted to resist said pressure against the edge of the shoe sole. 25

2. A shoe bottom attaching apparatus including, in combination, pressure-applying means adapted to engage with and apply pressure to a shoe sole over its entire area, pressure resisting means to hold a shoe in pressure receiving 30 position, additional pressure resisting means to engage the welt of the shoe, and pressure exerting means acting only on the portion of the pressure-applying means at the marginal area of the shoe sole. 35

3. A shoe bottom attaching apparatus including, in combination, pressure-applying means, means for holding a shoe in position to resist the pressure of said pressure-applying means against the shoe sole, and additional means 40 adapted to resist said pressure against the edge of the shoe sole, said additional means comprising disconnected elements and being adjustable to cooperate with shoes of different sizes and shapes. 45

4. A shoe bottom attaching apparatus including, in combination, pressure-applying means, means for holding a shoe in position to resist the pressure of said pressure-applying means against the shoe sole, and additional means 50 adapted to resist said pressure against the edge of the shoe sole, said additional means including a plurality of disconnected members adapted to overlie the welt of the shoe to resist the pressure of the pressure-applying means against the 55 edge of the sole, and being adjustable to cooperate with shoes of different sizes and shapes.

5. A shoe bottom attaching apparatus including, in combination, pressure-applying means, means for holding a shoe in position to resist 60 the pressure of said pressure-applying means against the shoe sole, and additional means adapted to resist said pressure against the edge of the shoe sole, said additional means comprising a holder secured to the shoe holding means 65 and adapted to support a plurality of disconnected members arranged to overlie the welt of the shoe to resist the pressure of the pressure-applying means against the edge of the sole, said members being independently adjustable vertically, horizontally and laterally to cooperate with 70 shoes of different sizes and shapes.

6. A shoe bottom attaching apparatus, including a base, a flexible pressure-applying member associated with said base, an annular inflatable 75

- member arranged between the base and the pressure-applying member, means rigidly to hold a shoe with the sole in position to receive pressure from the pressure-applying member exerted by the inflatable member, and means adapted to overlie the welt of the shoe to resist the pressure applied against the underside of the edge of the sole.
7. A shoe bottom attaching apparatus, including a base, a flexible pressure-applying member associated with said base, an annular inflatable member arranged between the base and the pressure-applying member, means rigidly to hold a shoe with the sole in position to receive pressure from the pressure-applying member exerted by the inflatable member, and means adjustable to cooperate with the particular shoe being acted upon for engaging the welt of the shoe to resist the pressure applied against the underside of the edge of the sole.
8. A shoe bottom attaching apparatus as set forth in claim 3, wherein the means for resisting the pressure against the edge of the sole includes a segmental U-shaped member having each segment independently rotatable and adjustable vertically, horizontally and laterally, whereby said members may be adjusted to operate with shoes of different sizes and shapes.
9. A shoe bottom attaching apparatus as set forth in claim 3, wherein the means for resisting the pressure against the edge of the sole includes a segmental U-shaped member supported by a holder secured to the shoe holding means and having each segment independently and removably mounted in said holder, whereby substitution and replacement of the segments may be made.
10. A self-contained pressure applying unit for a sole attaching machine, comprising a pad supporting means, a pressure pad supported thereby, a yoke arranged over the pad and supported by the pad supporting means, and a sole extension support sustained by the yoke.
11. A self-contained pressure applying unit for a sole attaching machine, comprising a pad box, a pressure pad in the pad box, a yoke arranged over the pad and supported by the pad box, a toe rest sustained by the yoke, and a sole extension support disposed around the toe rest and also sustained by the yoke.
12. Pressure applying apparatus for a sole attaching machine, comprising a pad box, a pad therein, a yoke extending over the pad, a swinging arm supported by the yoke, and a sole extension support carried by the arm and movable into position to contact with the margin of a sole upon the pad.
13. A self-contained sole attaching unit comprising a base, an inflatable pressure pad arranged thereon, a yoke carried by the base and arranged over said pad, and a sole extension support sustained by the yoke.
14. A sole attaching device, comprising a base, an inflatable pressure pad arranged thereon, a yoke carried by the base and arranged over said pad, and a sole extension support sustained by the yoke.
15. A self-contained pressure applying unit for a sole attaching machine, comprising a pad supporting means, a pressure pad supported there-
- by, a yoke arranged over the pad and supported by the pad supporting means, and a sole extension support associated with the yoke.
16. A self-contained pressure applying unit for a sole attaching machine, comprising a pad supporting means, a pressure pad supported thereby, a stationary yoke arranged over the pad and supported by the pad supporting means, and a sole extension support associated with the yoke.
17. A shoe sole attaching device, comprising a pad supporting means, a pressure pad arranged thereon, a yoke arranged over the pad and supported by the pad supporting means, sole supporting means, and sole extension supporting means, both of said supporting means being arranged to react against the yoke in resisting pressure applied to the sole.
18. A shoe sole attaching device, comprising a pad supporting means, a pressure pad arranged thereon, a yoke arranged over the pad and supported by the pad supporting means, sole supporting means, and sole extension supporting means, both of said supporting means being arranged to react against the yoke in resisting pressure applied to the sole and being adjustable independently of one another.
19. A shoe sole attaching device as in claim 18, wherein the sole extension supporting means comprises a sectional unit adaptable to shoes of different size and shape.
20. A shoe sole attaching device as in claim 18, wherein the sole extension supporting means comprises a sectional unit whose sections are independently adjustable for adaptation to shoes of different size and shape.
21. A sole attaching device, comprising a base, shoe supporting means arranged thereon, a yoke carried by said base and extending over the shoe supporting means, sole supporting means sustained by the yoke, sole extension supporting means sustained by the yoke, and common means for applying pressure to the sole and sole extension.
22. A shoe sole attaching device, comprising a base, a pressure pad arranged on the base, means supported by the base and extending over the pad, and means for supporting the shoe sole extension against bending when pressure is applied thereto, said supporting means being adaptable to soles of different size and shape and said supported means occupying a stationary position during the application of pressure to the shoe sole and taking the reaction of the sole extension supporting means in resisting the pressure.
23. A shoe sole attaching device, comprising a base, a pressure pad arranged on the base, means supported by the base and extending over the pad, means for supporting the shoe sole when pressure is applied thereto, and means for supporting the sole extension against bending when the sole is under pressure, said supporting means being adaptable to soles of different size and shape and said supported means occupying a stationary position during the application of pressure to the sole and taking the reaction of the sole supporting means and the sole extension supporting means in resisting the pressure exerted on the sole.
